UNITED STATES PATENT OFFICE.

MICHAEL SMITH, OF PORTLAND, OREGON.

ROTARY IMPACT-TOOL.

1,284,804.

Specification of Letters Patent. Patented Nov. 12, 1918.

Application filed April 16, 1918. Serial No. 228,883.

To all whom it may concern:

Be it known that I, MICHAEL SMITH, a citizen of the United States, and a resident of Portland, in the county of Multnomah 5 and State of Oregon, have invented a new and Improved Rotary Impact-Tool, of which the following is a full, clear, and exact description.

My invention relates to rotary impact tools 10 and particularly to that class of rock drills in which the drill steel may be given a rotary as well as an axial movement, and one of the main objects of my invention is to provide means which are at all times under 15 the control of the operator for accomplishing such rotation, thereby accommodating the drill to the different kinds and characters of rock and enabling him to use just the necessary force at all times.

Another object is to accomplish this rotation without the use of the spiral arrangements now known to be, these being difficult of lubrication and quickly subject to wear.

Another object is to provide means where- 25 by an operator may prevent the rotation of the drill steel, as when he is spotting a hole.

Another object is to provide means for preventing the axial actuation of the drill steel while permitting its rotation to meet 30 certain rock conditions.

Another object is to provide means yielding under resistance, as when the drill steel sticks for any reason, to prevent injury to the drill.

My invention is fully described in the following specification, of which the accom- 35 panying drawings form a part, in which like characters refer to like parts in each of the views, and in which—

Figure 1 is a vertical section taken through a drill constructed in accordance with my invention, as on the line 1—1 of Fig. 4.

Fig. 2 is a fragmentary section taken on the line 2—2 of Fig. 1.

Fig. 3 is a section taken on the line 3—3 of Fig. 1.

Fig. 4 is a section taken on the line 4—4 of Fig. 1.

Fig. 5 is a section taken on the line 5—5 of Fig. 1; and

Fig. 6 is an elevation, partly in section on the line 6—6 of Fig. 4, on a reduced scale.

Referring more particularly to the draw-

ings, 7 represents the cylinder of a power impact tool which will be referred to hereinafter as a drill and having a piston 8 adapted to reciprocate therein under the force of any suitable power fluid such as air, steam, or the like received through a pipe 11 from any suitable source of power and controlled through any convenient valve mechanism included in the casing 14 so as to be admitted into the cylinder 7 on opposite ends or sides of the piston in alternation through ports 9 and 10.

The cylinder is provided with a removable head 17 serving as a means to assemble the movable parts and to provide access thereto when necessary.

The cylinder is provided with an exhaust port or ports 20 at about its middle or at a position to exhaust after the piston 8 has made its full stroke in either direction. Fig. 1 shows the piston after it has made its down stroke with a corresponding impact against the tappet 22 interposed between the piston and the drill steel 21. Power fluid being then admitted through the port 10 will lift the piston causing it to pass upward beyond the exhaust port 20 and in position to be subsequently driven downward through the combined effect of gravity and the power fluid admitted through the port 9.

The drill steel is shown provided with a central port through which water may be 85 passed from any suitable source as for example through a passage 23 in the tappet 22 having constant communication with an annular passage 24 in the housing 24' to which the water may be led through a passage 25 from the upper part of the casing or cylinder structure as indicated in Fig. 6.

The drill steel is mounted in a bushing 26 so as to reciprocate but not rotate therein. The bushing 26, however, is journaled for 95 rotation in the shell 27 constituting the lower end portion of the stationary casing. The upper end of the shell 27 is provided with a ratchet 28 adapted to be rotated by the action of a pawl 29 carried by a horizontally reciprocatable slide block 30. See Figs. 2 and 3. This block is normally held in the retracted position of Fig. 2 by virtue of one or more springs 31 while its remote end or edge is beveled as shown at 30', the 105 direction of the beveling being rearward.

and downward or away from the springs 31. Above the block 30 is located a wedge shaped block 32 having a beveled face 32' adapted to coöperate directly with the face 30' of the 5 other block. The block 32 is adapted to reciprocate in the upper portion of the shell 27 and when forced downward by any suitable means it causes the actuation of the block 30 toward and against the force of the 10 springs 31 carrying with it the pawl 29 and causing thereby the apparent rotation of the ratchet 28 and bushing 26 in a clockwise direction as indicated in Fig. 3. When the 15 force acting downward upon the block 32 is relieved, however, the springs 31 act to return the block 30 to its normal position so bringing the pawl back to engage a succeeding tooth of the ratchet.

The block 32 is connected by means of a 20 strong spring 33 to the lower end of a plunger 34 slidable in the wall of the main casing and normally held upward by a spring 35. The upper end of the plunger is enlarged to provide a bearing surface for one end of 25 a bell crank 36 pivoted at 37, the other end of the bell crank projecting across the path of upward movement of the piston 8 so that when the piston is forced upward the bell crank is so rocked around its own pivot as 30 to force the plunger 34 downward. This force is communicated to the block 32 through the strong spring 33 causing thereby the rotation or partial rotation of the pawl as already described. By the interpolation, 35 however, of the spring 33 I insure that no damage to the implement can be occasioned by the obstruction or resistance applied to the drill steel tending to hold it from rotation temporarily.

40 When the piston 8 is forced toward the tappet 22 the spring 35 on the plunger again raises the same to carry the bell crank into the normal position of Fig. 1 ready for another operation, and the spring 31 returns 45 the block 30 and pawl 29 to normal position, ready for another ratchet actuation, it being noted that no spirally operated elements are employed.

The cylinder 7 is provided with two supplemental exhaust ports 38 and 39 normally closed by manually operated valves 40 and 41, respectively, the former being opened when it is desired to rotate the drill steel to permit the fluid under pressure in the cylinder to exhaust before the piston strikes against the tappet 22 and to thus prevent axial drill steel actuation, and the latter being opened when it is desired to actuate the drill steel axially and to not rotate the 55 same, as in spotting a hole, the power fluid in the cylinder being permitted to exhaust before the piston strikes against the bell crank 36.

It will thus be seen that I provide a drill 60 that is under thorough control, permits rapid

operation, is very simple in construction and operation, is composed of few parts not likely to get out of order, is light and compact, is readily assembled and disassembled, and is entirely practical.

70 While I have shown a preferred embodiment of the several features of the invention, I do not desire to limit myself thereto, as changes may be made thereover and come within the spirit of the invention and within the scope of the appended claims.

I claim:

1. In an impact tool, a casing having a cylindrical bore, a piston therein, said cylinder bore having end inlet ports and an exhaust port uncovered at each full piston stroke, a power fluid supply pipe connected with said end ports, a tool carrier, a ratchet thereon, a spring resisted plunger, means operable thereby for rotating said carrier and ratchet, a bell crank having one arm bearing on said plunger and the other arm arranged in the path of movement of said piston whereby said piston will rock said bell crank to actuate said plunger in each movement in one direction, and means operable by said piston in the other direction of movement for actuating the tool axially.

80 2. In an impact tool, a casing having a cylindrical bore, a piston therein, said bore having end inlet ports and a central exhaust port uncovered at each full piston stroke, a power fluid supply pipe connected with said inlet ports, a tool carrier, a ratchet thereon, a spring resisted slide block in said casing, 85 a pawl carried thereby for actuating said ratchet, a supplemental wedge shaped slide block, said slide blocks having opposed beveled surfaces whereby said first named slide block will be moved by the movement 90 in one direction of said second named slide block, a spring resisted plunger acting on said second slide block, a bell crank having one arm bearing on said plunger and the other arm arranged in the path of movement 95 of said piston, whereby said plunger will be actuated in each piston movement in one direction to rotate said carrier, and a tappet 100 operable by said piston in the other direction 105 of movement for actuating the tool axially.

110 3. An impact tool having a cylindrical bore, a piston therein, a power fluid supply pipe, a valve controlling the admission of fluid to opposite ends of said bore alternately, a tool carrier, means operable by 115 said piston in one direction of movement for rotating said carrier, means operable by said piston in the other direction of movement for actuating the tool axially, and means for rendering said carrier rotating means inoperative consisting of an exhaust port in 120 said bore uncovered before said piston has completed a stroke and a manually controlled valve for said exhaust port.

125 4. In an impact tool having a cylindrical 130

bore, a piston therein, a power fluid supply pipe, a valve controlling the admission of fluid to opposite ends of said bore alternately, a tool carrier, a tool therein, means operable by said piston in one direction of movement for rotating said carrier, means operable by said piston in the other direction

of movement for actuating the tool axially, and means for rendering said last named means inoperative consisting of an exhaust port in said bore uncovered before said piston has completed a stroke and a manually controlled valve for said exhaust port. 10

MICHAEL SMITH.
